(57) **CLAIM**

The ornamental design for a gate diagonal bracket, as shown and described.

DESCRIPTION

FIG. 1 is a perspective view of a gate diagonal bracket.

FIG. 2 is a front elevation view of the gate diagonal bracket shown in FIG. 1, the rear elevation view being a mirror image thereof.

FIG. 3 is a right side elevation view of the gate diagonal bracket shown in FIG. 2, the left side elevation view being a mirror image thereof.

FIG. 4 is a top plan view of the gate diagonal bracket shown in FIG. 2; and,

FIG. 5 is a bottom plan view of the gate diagonal bracket shown in FIG. 2.

The broken lines shown are included for the purpose of illustrating portions of gate diagonal bracket that form no part of the claimed design.

1 Claim, 2 Drawing Sheets
